(57) **CLAIM**

The ornamental design for an operation panel for facsimile machine, as shown and described.

DESCRIPTION

FIG. 1 is a perspective view of a multi-function device including an operation panel for facsimile machine showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is an alternate side view thereof;

FIG. 9 is an alternate bottom view thereof;

FIG. 10 is an alternate front view showing the lid in an open position; and,

FIG. 11 is another view thereof.
